(57) **CLAIM**

The ornamental design for a shear razor device, as shown.

DESCRIPTION

FIG. 1 is a bottom isometric view from the front left side of a shear razor device showing our new design;

FIG. 2 is a top isometric view looking from the front right side thereof;

FIG. 3 is the bottom isometric view of the invention exploded and shown in an open position of the shown;

FIG. 4 is the top plan view of the invention thereof;

FIG. 5 is the bottom plan view of the invention thereof;

FIG. 6 is left elevation view of the invention;

FIG. 7 is the right elevation view of the invention;

FIG. 8 is rear elevation view of the invention; and,

FIG. 9 is the front elevation view thereof.

In the drawings, the broken lines depict environmental subject matter and form no part of the claimed design.

1 Claim, 7 Drawing Sheets
